Arthur E. Bausenbach, Buffalo, N. Y.

Application February 22, 1945, Serial No. 118,082

Term of patent 7 years

(Cl. D13—1)

To all whom it may concern:

Be it known that I, Arthur E. Bausenbach, a citizen of the United States, residing at Buffalo, in the county of Erie and State of New York, have invented a new, original, and ornamental Design for an Airplane Hangar, of which the following is a specification, reference being had to the accompanying drawing, forming a part thereof.

Figure 1 is a front top perspective view of the airplane hangar embodying my design. Figure 2 is a rear top perspective view of the same.

I claim:

The ornamental design for an airplane hangar, substantially as shown.

ARTHUR E. BAUSENBACH.
